UNITED STATES PATENT OFFICE.

WILLIAM BERNSTEIN, OF JAMAICA PLAIN, MASSACHUSETTS.

HEEL REST.

Application filed July 10, 1920. Serial No. 395,406.

To all whom it may concern:

Be it known that I, WILLIAM BERNSTEIN, a citizen of the United States, residing at Jamaica Plain, in the county of Suffolk and 5 State of Massachusetts, have invented certain new and useful Improvements in Heel Rests; and I do hereby declare the following to be a full, clear, and exact description of the invention, such as will enable others 10 skilled in the art to which it appertains to make and use the same.

The present invention relates to certain improvements in foot rests employed in connection with the operation of motor vehicles.

15 It is desirable to provide some form of rest for the heel end of the operator's foot when manipulating any one of the several control pedals employed in connection with the operation of a motor vehicle. The use 20 of such a rest not only adds to the surety of control, but avoids the localized wear by the operator's shoe which would otherwise come upon the floor covering of the motor vehicle.

25 It is the object of the present invention to provide a new and improved form of heel rest which is compact, attractive in appearance, and so designed that the shoe may be readily engaged or disengaged, and held 30 firmly by the rest during the manipulation of the control pedals.

With this object in view the features of the invention consist in a heel rest of novel form and construction, which accomplishes 35 in a highly efficient manner the results enumerated.

In the simplest and most efficient form of the invention which has yet been devised, the rest consists of a substantially flat base 40 member having an upstanding flange in the general form of a U, the arms of which diverge, the base member and the flange being formed as a single integral member of rubber, rubber composition, or a like plastic 45 material.

In the accompanying drawings illustrating the preferred form of the invention, Figure 1 illustrates a perspective view of the improved heel rest; and Figure 2 is an elevation looking at the front side of the rest.

50 The illustrated embodiment of the present invention comprises a molded heel rest having a base portion 1 provided with an upstanding flange 2. The flange 2 is approximately U-shaped, with arms 3 diverging 55 from the base of the U toward the open end,

as shown clearly in Figure 1 of the drawings. By virtue of these straight, diverging arms the flange is enabled to engage and firmly hold heels of varying size, the operator merely thrusting the heel of the shoe between the arms until it is gripped thereby. In order to facilitate disengagement of the heel from between the arms of the flange, and at the same time avoid the possibility 60 of marring the operator's shoe, the interior walls of the flange are smooth and substantially normal at all points to the plane of the base. The outer walls of the flange 65 incline outwardly from the upper edge of the flange toward the junction of the flange with the base portion, to reinforce the flange and afford a rigid and secure connection between the flange and base portion. In order to facilitate the entrance of the heel between 70 the diverging walls of the flange, the front ends of the arms 3 slope downwardly toward the surface of the base portion, emerging therewith, as shown in the drawings. The base is provided with a substantially 75 rectangular recess 11 in the upper surface in which the flange is received, this recess being surrounded by a raised or thickened margin, about which are disposed fastener receiving openings 10, having the usual 80 washers 12 embedded therein. In the preferred embodiment of the invention the marginal portion of the base is further strengthened by reinforcing ribs 14 which connect annular projections 15 surrounding 85 the fastener receiving openings at each of the four corners of the base. It will be observed that according to this construction the U-shaped flange is molded into the recess 11 along its entire length and into 90 the surrounding raised flange at the back and two front corners, thus providing a substantially rigid construction with the use 95 of a minimum of material.

The heel rest as a whole is preferably 100 made of rubber, rubber composition, or a like plastic material, and serves as a convenient rest for the operator which will not damage the most delicate shoe, and which is impervious to the corrosive action of 105 water or other fluid, retaining its attractive appearance throughout the period of use.

Having thus described the invention, what is claimed is:—

1. A heel rest comprising a base portion 110 of rubber and an upstanding retaining flange molded thereon having diverging

walls adapted to fit and hold different heel sizes.

2. A heel rest comprising a base portion and an upstanding retaining flange molded thereon adapted to fit and hold different heel sizes, the inner walls of the retaining flange being arranged substantially normal to the plane of the base portion, and the outer walls of the retaining flange being inclined outwardly from the top of the flange to the base to form a reinforcement for the flange.

3. A heel rest comprising a base portion of rubber having a plurality of fastener receiving openings in the marginal portions thereof, a plurality of ribs upon the upper

surface of the marginal portions of the base between said fastener receiving openings and an upstanding retaining flange molded upon the upper surface of the base having diverging walls adapted to fit and hold different heel sizes. 20

4. A heel rest comprising a base portion and a substantially U-shaped flange having straight, diverging walls sloping toward the 25 surface of the base portion at their front ends, the base and flange being formed as a single integral construction, and fastener receiving openings formed in the marginal portion of the base.

WILLIAM BERNSTEIN.
